UNITED STATES PATENT OFFICE.

NICHOLAS DOWNES, OF SYRACUSE, NEW YORK.

FILTER.

SPECIFICATION forming part of Letters Patent No. 231,480, dated August 24, 1880.

Application filed May 3, 1880. (No model.)

To all whom it may concern:

Be it known that I, NICHOLAS DOWNES, of Syracuse, in the county of Onondaga, in the State of New York, have invented new and useful Improvements in Water-Filters, (not patented to me, nor with my knowledge or consent, in any foreign country,) of which the following, taken in connection with the accompanying drawings, is a full, clear, and exact

10 description.
This invention relates to the class of water-filters in which the unfiltered water passes from a refrigerating vessel or tank in the upper part of the apparatus through a conduit 15 or pipe to the bottom of the filtering medium, and thence up through the latter to a water-space surrounding the aforesaid refrigerating-tank.

The invention consists in an improved combination and arrangement of the internal parts of the water filtering and cooling apparatus, whereby the same is rendered adjustable and capable of being readily repaired and maintained in proper working condition, all as hereininafter more fully described, and specifically set forth in the claims:

The invention is clearly illustrated in the accompanying drawings, wherein—

Figure 1 is an elevation of the water-filter 30 with the front half of the case removed to show the interior arrangement. Fig. 2 is a vertical section of same; Fig. 3, a top view with the cover removed; Fig. 4, a horizontal section on line $\alpha\alpha$ in Fig. 2. Fig. 5 is an enlarged inverted view of the sponge-holder; and Figs. 6 and 7 are plan and side views, respectively, of the means of attaching the sponge-holder to the water-conduit.

Similar letters of reference indicate corresponding parts.

A denotes the outer case of the water filtering and cooling apparatus, formed of a cylindrical or other desirable shaped deep body provided with a water-tight bottom.

B is a vessel or tank tapered from the top to the bottom, and provided on top with an outward-turned rim or flange, b, by which it is supported on the top edge of the case A.

f' are two perforated diaphragms arranged 50 in the lower compartment of the case and con-

taining between them the packing or filtering medium C.

The lower diaphragm is supported a sufficient distance above the bottom of the case to form underneath it a chamber or receptacle, R, for the sediment of the water in process of filtering.

c is a pipe extended from the tank B through the two diaphragms f' and the interposed packing C, and communicating with the bottom chamber, R.

The pipe c is screw-threaded externally, and by means of nuts n n applied thereto at opposite sides of the lower diaphragm f' the said parts are connected.

Upon the upper diaphragm f' is placed a cone-shaped brace, v, through the center of which the pipe c passes. By means of a nut, n', on the said pipe at the top of the cone v, any desired pressure can be applied to the latter, which, in turn, transmits said pressure to the diaphragm f', upon which it rests.

The base of the cone, by its annular enlarged and concentric bearing, distributes the pressure over the diaphragm and braces the same. This adjustable connection of the upper diaphragm with the pipe c furnishes a very simple and efficient means for conferring the desired degree of compactness to the filtering material interposed between the two diaphragms.

The upper extremity of the pipe c protrudes through the bottom of the tank B, and is provided underneath the same with a nut, r, and a washer or gasket interposed between said nut and the under side of the tank, which, in conjunction with a nut, s, on top of the bottom of the tank, forms a water-tight joint around the pipe.

d is a skeleton-cone having near its base a detachable cross-bar, e, provided with a screw-threaded central aperture, by which it is screwed on the upper extremity of the conduit c. Within the cone d is placed a sponge, which, being brought to bear on the end of the pipe c, serves to strain the water before it enters the said pipe. By screwing down the cone d the pressure of the end of the pipe c on the sponge can be increased, so as to compress the latter any desired degree, and thus regu-

late the flow of the water through the same. The cone *d*, bearing with its base against the bottom of the tank, serves, in addition to the functions before described, to draw the tank 5 *B* downward, thus firmly securing it in its position, and at the same time tightening its joint with the top edge of the case.

It will be observed that by the described combination and arrangement of the internal 10 parts of my improved filterer the sponge, while perfectly secure in its position, is easily accessible for cleaning or renewing.

By removing the sponge-holder and the nut *s* the tank *B* can be taken out and cleaned or 15 repaired when necessary. The removal of the tank gives access to the water-space above the filtering medium, and if it is desired the latter can be cleansed, without disturbing it in its position, by closing the upper end of the pipe 20 *c* and pouring water into the compartment above the filtering medium. The stopper *i* at the base of the case *A* being removed allows the water, as it issues from the bottom of the filtering medium, to escape through the opening 25 at the base of the case. This drenching process carries off the impurities which have accumulated in the filtering material, and also washes out the bottom of the case.

My improved arrangement of the internal 30 parts of the apparatus also allows the same to be drawn bodily out of the case without the necessity of unsoldering joints or rupturing other permanent parts.

Having thus described my invention, what I 35 claim as new, and desire to secure by Letters Patent, is—

1. The combination, with the case *A*, of the

tank *B*, secured removably in its position by its top rim, *b*, resting upon the top edge of said case, and by the screw-threaded pipe *c*, passing through the diaphragms *f f* and through the bottom of the tank *B*, and provided at opposite ends with tightening-nuts, substantially as set forth. 40

2. The combination, with the case *A* and the removable tank *B*, of the pipe *c*, confined at its lower end and having a screw-threaded upper end, and the sponge-holder consisting of the skeleton-cone *d* and the cross-bar *e*, connected detachably therewith and provided at its center with a threaded aperture fitted to the threaded end of pipe *c*, substantially as shown and described. 45

3. In combination with the packing *C*, the diaphragms *f f*, externally-threaded pipe *c*, nut *n*, cone *v*, and nut *n'*, substantially as described and shown, for the purpose set forth. 50

4. The combination and arrangement, with the case *A*, of the diaphragms *f f*, packing *C*, threaded pipe *c*, nuts *n n'*, cone *v*, removable tank *B*, and the sponge-holder *d*, having the female-threaded cross-bar *e*, all substantially in the manner described and shown, for the purpose set forth. 55

In testimony whereof I have hereunto signed my name and affixed my seal, in the presence of two attesting witnesses, at Syracuse, in the county of Onondaga and State of New York, this 2d day of April, 1880. 60

NICHOLAS DOWNES. [L. S.]
